UNITED STATES PATENT OFFICE.

JABEZ H. GILL, OF PHILADELPHIA, PENNSYLVANIA.

CARTRIDGE-PRIMER.

SPECIFICATION forming part of Letters Patent No. 225,591, dated March 16, 1880.

Application filed December 17, 1879.

To all whom it may concern:

Be it known that I, JABEZ H. GILL, of Philadelphia, in the county of Philadelphia and State of Pennsylvania, have invented certain Improvements in Cartridge-Primers, of which the following is a specification.

My invention relates to primers for cartridges; and it consists in the employment of an anvil consisting of a thin circular plate or disk having on one face a rib or bar, the disk serving, when the anvil is applied to the cap or primer, to cover the fulminate, and by the accuracy of its fit to protect the same against moisture, while the rib or bar serves as a support upon which to explode the fulminate.

Figure 1 represents a face view of the open or inner side of my improved primer; Fig. 2, a vertical central section of the same on the line *x x* of Fig. 1; Fig. 3, a similar view of the primer after being fired or exploded; Fig. 4, a perspective view of the anvil detached, and Fig. 5 a sectional view of a shell with my primer applied.

In the accompanying drawings, *A* represents the primer as a whole; *b*, the cap, and *c* the anvil.

The cap is of the form commonly employed for cartridge-primers, and the anvil *c* consists of a thin disk of brass or similar stiff metal, having on one face a rib or bar, *d*, extending entirely across the same, and of such thickness that when the anvil is applied to the cap it shall come flush with or extend beyond the front of the cap, as shown in Fig. 2. Fulminate *e* is applied to the cap as usual, after which the anvil is inserted within the cap and its flat face pressed closely against the fulminate, as shown in Fig. 2, this operation being performed by suitable dies, and the mechanical fit of the anvil within the cap being found in practice to be so perfect as to entirely prevent the access of moisture to the fulminate.

The primer thus constructed is seated within the recess of the cartridge-head, as shown in Fig. 5, the bar *d* of the anvil bearing at its ends upon the bottom of said recess, while the concave form of said bottom affords a space between it and the anvil for the passage of the spark or flash.

When the primer is exploded or fired the thin disk of the anvil *b* folds down at each

side of the bar *d*, as shown in Fig. 3, permitting the flash or spark to pass freely from the primer.

While in practice the disk is found to form a water-tight covering for the fulminate, a drop of varnish may be placed over the disk as an additional precaution.

It is apparent that the edges of the bar *d* may, if desired, be beveled or rounded off to permit the more ready passage of the spark, though the form shown is considered best; and it is also obvious that, instead of providing the disk with the straight bar or rib, the latter may be made in other forms—as, for example, with three arms radiating from the center of the disk.

If desired, tin-foil may be introduced upon the fulminate, as usual, prior to the application of the anvil.

The anvil may be pressed out in a die from solid metal, or from a rolled bar of *T* form in cross-section, the latter course being considered preferable.

I am aware that it is old to insert a disk of tin-foil within a cap over the fulminate, and then insert a straight bar-anvil into the cap upon and across the foil, and fasten said anvil by crimping the edge of the cap inward thereon, and this I do not claim.

My method of constructing the primer in a circular or disk form, with the anvil formed in one piece therewith, is advantageous not only in being cheaper to construct and easier to apply mechanically, but in that it prevents the distortion of the cap-cylinder, which must fit closely and accurately in the cartridge-shell in order to serve as a gas-check and prevent leakage at the base. The disk of my primer, bearing around its entire circumference against the cap, has sufficient friction to retain it and the anvil firmly in place, and as it is forced to its place the disk serves to maintain the true circular form of the cap. In the insertion of the bar-anvil, on the contrary, the ends bearing in opposite sides of the cap tend to, and actually do, distort and elongate the cap to such an extent that the gases find their way past its exterior when the cartridge is ignited.

A marked advantage of my primer arises also from the fact of the thin portion of stiff metal being sustained at the middle, in conse-

quence of which the metal yields first at the outer edge, the gas being confined and its action intensified, and its pressure first caused to act against the inside of the cap, so as to force the same outward against the walls of the pocket in which it is seated.

Having thus described my invention, what I claim is—

1. The herein-described anvil, made complete in one piece, with a thin circular disk and a raised bar thereon, as shown and described.
2. The combination of a cap or primer, A,

and an internal anvil, made in one piece, with a thin disk to hold the fulminate in place and a raised bar to serve as an anvil.

3. A bar-anvil provided with thin side portions adapted to retain the fulminate in place within the cap or primer and to fold down under the pressure of the gases, as shown and described.

JABEZ H. GILL.
